UNITED STATES PATENT OFFICE.

HERMAN O. E. BEINDORF, OF HOMESTEAD, COLORADO.

AUTOMATIC DUMPING DEVICE.

1,234,717.

Specification of Letters Patent. Patented July 31, 1917.

Application filed September 5, 1916. Serial No. 118,503.

To all whom it may concern:

Be it known that I, HERMAN O. E. BEINDORF, a citizen of the United States, residing at Homestead, in the county of Pueblo 5 and State of Colorado, have invented certain new and useful Improvements in Automatic Dumping Devices, of which the following is a specification.

The present invention has to do with improvements in automatic dumping devices as particularly adapted for use in the excavation of wells, in the sinking of mine shafts, or other operations involving the removal of material through the instrumentality of 10 hoisting rigs. The invention has for its object to provide simple means, including a vertically arranged bucket hoist, for automatically directing the bucket to dumping position.

20 It is further an object to provide locking means with which the bucket directing means aforesaid coöperates to hold the latter maintaining the bucket in an outwardly swung position in relation to the well or mine shaft while the bucket is being dumped, 25 said dumping action being also automatic in character so that the apparatus serves not only to facilitate the operations but to effect saving of time and labor for carrying 30 on the same.

In addition to the foregoing it is comprehended to employ that type of locking means which will automatically release the bucket directing means when the bucket, after 35 dumping, is again actuated to return it to position within the shaft.

These and such other objects as may hereinafter appear are attained by the novel construction, combination and arrangement of 40 parts to be hereinafter specifically described and claimed. Reference will now be had to the accompanying drawings forming a part of this specification, wherein:—

Figure 1 is a side elevation of an apparatus constructed in accordance with my invention, parts being broken away and shown in section;

Fig. 2 is a front elevation;

Fig. 3 is an enlarged vertical sectional view on the line 3—3 of Fig. 2;

Fig. 4 is a top plan view of the apparatus; and

Fig. 5 is a detail view in side elevation of the automatic bucket dumping means.

55 Referring to the drawings and specifically describing the invention, 1 designates

a suitable gallows frame at the upper portion of which are arranged spaced standards 2 between which is mounted a sheave 3 accommodating the hoisting cable 4 carrying 60 the bucket 5. For the purpose of convenience in this description the parts 4 and 5 will be referred to as the bucket hoist. Projecting laterally from the frame 1 are a pair of supporting arms 6 at the end portion of 65 which is supported a transverse support 7, the latter having trunnions at its extremities journaled in the arms 6 to permit of rotation of said transverse member. Depending from this member 7 is a thrust arm 8 70 which preferably consists of spaced side members 9 converging at the lower extremities between which is received a friction roller 10 adapted to coöperate with the hoisting cable in the operation of the apparatus, 75 as will be hereinafter more fully explained.

It will be observed by reference to Fig. 1 that the arm 8 extends downwardly at an incline so that the lower extremity will normally lie in the path of movement of the 80 bucket as it is raised from the excavation, the arm being held in such normal position by the stop member 11 which is supported by the platform support 12. It will be understood that upon this last mentioned support the necessary mechanism for mechanically operating the bucket hoist may be positioned, as diagrammatically indicated at 13.

Upon lifting movement of the bucket hoist the arm 8 is impinged by the bucket, 90 a cushion spring 14 being provided just above the bail of the bucket to take up the impact. After impingement as above referred to, the arm 8 is carried upwardly with the bucket hoist moving in an arc at 95 one side of the gallows frame. The arm thrusts the bucket laterally from the frame out of the plane of its initial path of movement and when the arm has reached the horizontal dotted line position shown in 100 Fig. 1 it is automatically engaged with a locking member 15 which is supported between the lower end portions of the standards 2, as shown most clearly in Fig. 2 of the drawings. The locking member 15 is 105 held to one side so as not to interfere with the operation of the cable by means of a spacing washer 16. As will be noted particularly by reference to Fig. 3, the locking member 15 consists of the lower hook terminal 15' and the upper curved arm 15'', said locking member normally assuming a 110

vertical position so as to lie in the path of movement of the cross bar 17 carried by the side members 9 of the arm 8. This bar automatically engages with the hooked extremity of the locking member when the arm reaches the horizontal position above referred to, and upon lowering movement of the bucket toward its dumping position.

At one side of the frame is conveniently arranged the bucket dumping means or platform 18 which is pivotally supported at one side as indicated at 19 and provided with a counter-balance weight arm 20. The platform 18 furthermore is provided with diverging guide arms or standards 21 so that as the bucket 5 is lowered it will be guided by said standards onto the platform 18. This platform is immediately overbalanced and the material from the bucket 20 thereupon dumped. The operation of returning the bucket to its normal excavating position involves the raising of the bucket until it impinges the outer end portion of the arm 8 which is held in its horizontal position by the member 15. A continued lifting movement of the bucket hoist raises the arm 8 to the inclined dotted line position shown in Fig. 1, whereupon the rod 17 passes over the curved upper end of the locking member 15. Lowering movement of the bucket is now free to take place inasmuch as the rod acts upon the rear edge of the locking member to move it out of engaging position with respect to the rod and the arm will consequently return to its normal full line position shown in Fig. 1 as the bucket is lowered to its initial position.

It will be apparent from the foregoing description that the excavating operation above described may be carried out by a single operator inasmuch as the dumping operation is entirely automatic and under the control of the bucket hoist. The apparatus is extremely simple in its construction and may readily be used for various purposes aside from excavating operations, such for instance as removing material from cars, tanks or other receptacles by means of a vertically operated hoist.

50 Slight changes may be made in the details of construction without departing from the spirit of the invention and within the scope of the appended claims.

Having thus described my invention, what I claim as new is:—

1. In apparatus of the class described, the combination with a frame and bucket hoisting means, of an arm movable incident to hoisting action for directing the bucket to dumping position, a hook member mounted on said frame for free swinging movement and engageable at one end with the arm to support the same during lowering of the bucket for dumping, the other end of said hook member being arranged for en-

gagement by the arm incident to lifting of the bucket from the dumping position to thereby shift the engaging end of said hook member out of engaging relation with respect to the arm, whereby to effect release 70 of the latter.

2. In apparatus of the class described, the combination with a frame and bucket hoisting means, of actuating means arranged in the path of movement of the bucket hoist 75 operable during hoisting movement to positively direct the bucket to dumping position, and means engageable with the actuating means to hold the latter during dumping of the bucket, said holding means having a portion arranged to be impinged upon movement of the actuating means incident to return of the bucket to initial position to thereby effect release of said actuating means.

3. In apparatus of the class described, the combination with a frame and bucket hoist, of means for directing the bucket to dumping position comprising a member pivotally connected to the frame and inclining downwardly into the path of movement of the bucket for impingement thereby, said member being operable with the bucket hoist to positively thrust the bucket laterally away from the frame during hoisting action into dumping position, and locking means carried by the frame in position to be engaged by the pivoted member aforesaid to sustain the latter during the dumping operation, said locking means having a hooked terminal for supporting the pivot member and an arm at its other terminal engageable by said pivoted member when the latter is actuated to lift the same whereby to withdraw the hooked terminal from its engaging position to thereby release said pivoted member.

4. In apparatus of the class described, the combination with a frame and bucket hoist, of means for directing the bucket to 110 dumping position comprising a thrust arm pivotally supported at one side of the frame, said arm extending beyond the frame and having its free end movable in a plane at the opposite side of the frame, the free end 115 of the arm normally lying in the path of movement of the bucket and being operable upon hoisting to direct the bucket to dumping position, and a member carried by the frame in the path of the arm and constituting a holding and releasing means, said means at one end being formed to engage and hold the thrust arm against downward movement during the dumping action of the bucket and constructed at its other end to 125 provide for movement of the first mentioned end out of engaging relation when the thrust arm is elevated from its engaged position.

5. In apparatus of the class described, the 130

- combination with a frame and bucket hoist, of an arm depending from the frame into the path of movement of the bucket and movable therewith upon lifting movement 5 of the bucket, an automatic acting locking member carried by the frame, means on the arm engageable by the locking member to sustain the same when said arm has reached a predetermined position to 10 thereupon permit lowering of the bucket into dumping position, said arm during raising movement thrusting the bucket out of the plane of its initial path, said locking member having a releasing element automatically operated upon subsequent lifting 15 of the bucket to permit return of the arm and bucket to normal position.
6. In apparatus of the class described, a frame, a support extending laterally from 20 said frame, an arm pivotally connected to the outer portion of said lateral support and depending downwardly at an incline, stop means holding the arm in normal operative position, a hoisting bucket mounted on the 25 frame and adapted to impinge the arm upon hoisting movement, said arm swinging the bucket to one side of the frame for dumping, and a locking member disposed above on the frame and engageable with the arm 30 to hold the latter while the bucket is dumped, said locking member having a releasing arm arranged above the arm when in the engaged position aforesaid engageable by the arm incident to return of the 35 bucket to initial position.
7. In apparatus of the class described, the combination with a frame and bucket hoist, of an arm depending from the frame into the path of movement of the bucket 40 and movable therewith upon lifting movement of the bucket, a locking and releasing member carried by the frame in the path of movement of the arm, means on the arm engageable with one end of the member 45 when said arm has reached a predetermined position to sustain and thereupon permit lowering of the bucket without movement
- of the arm into dumping position, said arm during raising movement thrusting the bucket out of the plane of its initial path, 50 said member having its opposite end arranged to be automatically operable by the arm to effect release upon subsequent lifting of the bucket to permit return of the arm and bucket to normal position, and means to 55 automatically dump the bucket upon lowering of the latter to dumping position.
8. In automatic dumping devices of the class described, the combination of a frame, a bucket hoist mounted thereupon, a thrust 60 arm pivotally connected to said frame in position for coöperation with the bucket hoist, said arm being arranged for movement with the bucket during lifting operation of the latter, a locking member mounted upon the 65 frame, means carried by said thrust arm for interlocking with said locking member when the arm has reached a predetermined position to hold the arm inoperative during dumping of the bucket, and means to automatically dump the bucket when the latter is lowered into dumping position, the 70 locking member aforesaid having means to effect release of the thrust arm upon return of the bucket to initial position.
9. In apparatus of the class described, the combination with a support and bucket hoisting means thereon, of actuating means arranged in the path of movement of the bucket hoist operable during hoisting of the 75 bucket to direct said bucket to dumping position, and engaging means disposed in the path of the actuating means to automatically engage with the same to sustain the latter when said actuating means has been moved 80 a predetermined distance during the hoisting operation, said engaging means having one end thereof arranged in position to be impinged by the actuating means upon further movement thereof, incident to return of the bucket to initial position subsequent to dumping.

In testimony whereof I affix my signature.
HERMAN O. E. BEINDORF.
